UNITED STATES PATENT OFFICE.

GERARD SICKELS, OF BROOKLYN, NEW YORK.

FRICITION-CLUTCH.

Specification of Letters Patent No. 8,782, dated March 2, 1852.

To all whom it may concern:

Be it known that I, GERARD SICKELS, of Brooklyn, in the county of Kings and State of New York, have invented a new and Improved Friction-Clutch; and I do hereby declare that the following is a full, clear, and exact description of the construction and operation of the same, reference being had to the annexed drawings, making a part of this specification, in which—

Figure 1, is an external view of the clutch. Fig. 2, is a descriptive view, the several parts of the clutch being detached. Fig. 3, is a side view of the boxes which contain the segments. Fig. 4, is a face view of the boxes, showing the segments, and the screw rods and nuts by which the segments are graduated.

Similar letters of reference indicate corresponding parts in each of the several figures.

The nature of my invention consists in a peculiar manner of operating two or more segments, by which operation the segments are made to bind in a V-shaped collar or be freed from it as desired; the binding of the segments in the collar causing motion to be transmitted to certain parts of machinery to which the clutch may be properly applied or stopping the motion of said parts of machinery by freeing the segments from the collar; the segments are operated by means of levers having arms attached to them, the arms being also attached to boxes in which the segments are fitted or placed. The arms and levers are so arranged that when the segments are bound or pressed in the collar they will not relax or become free from the collar without the application of some extraneous force.

My invention further consists in the employment or use of the V collar and segments inclosed in the boxes and arranged in a manner which will be hereafter described, in combination, with the manner of arranging the levers and arms.

To enable others skilled in the art to make and use my invention I will proceed to describe its construction and operation.

50 A, Figs. 1, 2, and 3, represents a shaft.

B, Figs. 1, and 2, is a collar attached permanently to the shaft, and having a square flanch (a) at one end, the flanch forming right angles with the shaft; on two of the 55 sides of this flanch are projections (b). One only is seen, see Fig. 2, the other pro-

jection being on the opposite side. These projections form right angles with the face of the flanch (a) and are consequently parallel with the shaft A, and collar B; on these 60 projections are placed two levers (C). One only is seen, Figs. 1, and 2. The levers are precisely similar but are placed on the projections (b) in a reverse manner as will be hereafter explained. The fulcrum of the 65 lever is seen at (c); each lever has two arms (d) (d') which are connected to the lever C, by pivots (e) (e) as shown in Figs. 1 and 2. The outer ends of these arms are attached to boxes D, D, by pivots (f) (f); 70 one side (g) of these boxes bear against the face of the flanch (a) see Figs. 1 and 2; within the boxes are placed segments E, E, Figs. 3, and 4, a segment in each box. The segments work freely in the boxes and are 75 adjusted within them by screw rods (h) see dotted lines Fig. 4, which are operated by nuts (i). It will be seen that the screw rods are attached to the outer sides of the segments and pass through to the outer ends 80 of the boxes and that by turning the nuts (i) the segments may be brought nearer, or removed farther from the shaft, A.

F is a collar having a V groove in it see Fig. 2. This collar is placed loosely 85 on the shaft A. The inner ends of the segments are also V shaped see Fig. 3, and fit in the V recess in the collar. The dotted lines in Fig. 4, show the position of the collar. Now the binding or the pressure 90 of the segment around the collar gives motion to it, it being remembered that the collar F, is placed loosely on the shaft and that the segments and boxes move with the shaft at all times whether the segments bind 95 in the collar or not. This being understood it now remains to be shown how the segments are operated so that they can be made to bind in the collar or be relieved from it, and also when the segments do bind in the 100 collar, how they are prevented from reacting and becoming loose from the collar. This will be clearly seen by referring to Figs. 1, and 2. The arms (d) (d') are attached by pivots (f) (f) to the boxes D, D, 105 as has been before stated, and their opposite ends are attached to the lever C, by pivots (e) (e). Now it will be seen that the arms pass each other and are secured at opposite ends of the lever C. The consequence is 110 that when the end or shank (j) of the lever C, is turned upward in the direction indi-

cated by the arrow 1, the arms (d) (d') will be distended and the boxes D, D, and segments E, E, will be thrown or moved outward from the collar F, see Fig. 2, and that by the shank (j) of the lever C, being moved downward the boxes and segments will be thrown or moved toward the collar. The levers C are operated by means of the sliding collar G, Figs. 1, and 2 which vi-
10 brates or moves over the stationary collar B. This collar G, has slots (k). One only is seen, in which pins (l) in the shank j of the lever C, work. The sliding collar G, has also a groove (m) around it in which
15 the forked end of a lever may fit and by which the collar G, may be moved or vibrated, the moving or vibrating of the collar G, causing the levers C, to be turned, and the boxes and segments thrown from or
20 toward the shaft. It will be understood that the segments are so adjusted in the boxes by means of the screw rods (h) and nuts (i) as to bind in the collar when the boxes are thrown toward the shaft. Now when
25 the segments are bound in the collar F, they will remain so unless the sliding collar G, is moved, because the arms (d) (d') are attached to the levers C, in such a manner that the pivots (e) (e) or points of attachment are beyond the line of pressure X, X, and are prevented from going beyond a
30 certain distance. Consequently there can be no reaction, and the segments can not be released or freed from the V collar without the necessary extraneous force.
35

A pulley wheel, or shaft, may be attached to the collar F. In the drawings Figs. 1 and 2, a pulley H, is represented. Thus power may be transmitted from the shaft
40 A, to the pulley H, or vice versa, according as the vibrating slide G, is moved.

The clutch is not liable to get out of order,

is not expensive and in practice works well. It requires no extraneous power to keep the segments bound in the V collar, as has been
45 shown, after the connection is made.

I do not confine myself to any particular shape or form of levers C, or arms (d) (d').

It has been mentioned that the lever upon the opposite side of the flanch (a) was placed in a position reverse from the one shown. This is done in order to equalize the strain or pull upon the sliding collar G. The collar G, is prevented from turning on the collar B, by means of pins (o) (o) attached to the flanch (a) and pins fitting or working in recesses in the collar G, see dotted lines Fig. 2, or in other equivalent way.

Having thus described the nature and 60 operation of my invention, what I claim as new and desire to secure by Letters Patent, is—

1. The arrangement of the levers C, and arms (d) (d') for operating the segments E, E, substantially as shown and described, by which arrangement the segments are made to bind in the V collar F, or be relieved from it as desired, the segments when bound in the collar remaining in that state, the points or pivots (e) (e) having passed the line of pressure, unless acted upon by some extraneous force, as the moving of the vibrating slide G.
65

2. I claim in combination with the arrangement of levers and arms, the V collar F, and segments E, E, said segments being adjusted by screw rods (h) and nuts (i) as set forth.
